UNITED STATES PATENT OFFICE.

FREDERICK A. HEROUX, OF OAKLAND, CALIFORNIA.

DESIGN FOR A BAKE-OVEN.

57,432.

Specification for Design.

Patented Mar. 29, 1921.

Application filed September 10, 1919. Serial No. 323,016. Term of patent 7 years.

To all whom it may concern:

Be it known that I, FREDERICK A. HEROUX, a citizen of the United States, residing at Oakland, in the county of Alameda and State of California, have invented a new, original, and ornamental Design for Bake-Ovens, of which the following is a specification.

The figure is a perspective view of an oven, showing my new design.

I claim:

The ornamental design for a bake oven, as shown.

In testimony whereof I affix my signature.

FREDERICK A. HEROUX.
